Primary Examiner—James R. Largen
Attorney, Agent, or Firm—Martin E. Gerry

[57] CLAIM

The ornamental design for a pet carrier, as shown and described.

DESCRIPTION

FIG. 1 is a perspective view taken from the top, front and one side of a pet carrier showing my new design;

FIG. 2 is a front elevational view thereof;

FIG. 3 is a rear elevational view thereof;

FIG. 4 is a bottom plan view thereof;

FIG. 5 is an elevational view taken from one end thereof, the opposite end being the same as the end shown; and

FIG. 6 is a top plan view thereof.
